PRIMARY EMISSION CONTROLLED TUBE

George D. O'Neill, Manhasset, N. Y., assignor to Sylvania Electric Products Inc., a corporation of Massachusetts

Application November 23, 1948, Serial No. 61,703

11 Claims. (Cl. 313—103)

The present invention relates to electron tubes, more particularly to the type of positive-grid tubes including a secondary emitter electrode. Tubes of this class are disclosed in U. S. Patents Nos. 2,707,771 of May 3, 1955; 2,679,591 of May 25, 1954; and 2,677,057 of April 27, 1954, all of which are assigned to the assignee of the present invention.

Quick-starting requirements, and conservation of energy needed to heat a cathode encourages the use of directly heated filamentary cathodes, coated with electron-emissive material. Differences among positive-grid tubes as to the length of cathode wire that is coated lead to variations in the space-charge-limited currents among those tubes. This in turn leads to the possibility of excess drain imposed by the tube on a power supply of limited capacity, and to possibility of excess internal power dissipation and consequent deleterious heating of the tube elements; conversely, the current may be lower than desired with resultant lowered performance. Accordingly, an object of this invention is to provide a novel positive-grid tube, such that there will be improved uniformity of space-charge-limited current among tubes of one type.

In positive-grid tubes, there is a tendency of the electron stream to approach not only the active portions of the grid, but additionally the metallic connections and supports for the positive grid outside the active region, thus reducing tube efficiency. A further object of the invention is to improve tube efficiency, more specifically to concentrate the electron stream in the region where it can be efficiently utilized and will effect the intended functions.

An additional object of the invention is to reduce the current density in the cathode surface without changing the specified value of cathode current.

In dynatrons or positive-grid tubes having a secondary-emitting electrode or dynode as described in the copending applications mentioned above there is the possibility that secondary electrons will penetrate the grid and affect the primary current under some conditions. This tends to render the tube unstable and, accordingly, a further object is to avoid the adverse effects of such secondary-electron penetration.

The foregoing purposes are achieved by including an apertured control electrode between the cathode and the positive grid which is of such form as to confine the electron stream to the active portion of the grid, thus improving efficiency. This control electrode may be operated at cathode potential or it may be negative with respect to cathode, thus fixing the value of the cathode current and permitting the use of cathodes of larger extent without increasing the current. The resulting current-density in the cathode surface is consequently reduced.

Comparatively wide variations should be expected in the extent of electron-emissive material on the cathode due to the intrinsic nature of its processing, and this would cause correspondingly wide variations in cathode current. The control electrode, which is a centrally apertured disc in the illustrative embodiment, thus regulates the space-charge-limited current. Unlike the cathode, the control

2

electrode can be made and positioned with a high degree of accuracy with resulting uniformity of current characteristics.

This electrode controls and stabilizes not only the primary electron current, but in dynatron tubes this electrode tends to minimize the effect on the primary emission that may otherwise be caused should secondary electrons from the dynode penetrate the grid.

The electrode between cathode and the positive grid 10 serves the further purpose of enabling measurement of ionization in the cathode-grid region, which is a valuable check on the quality of the tube not readily determinable in tubes of the forms in the aforementioned copending applications. When operating the tube, with the electrode 15 slightly negative as it will be when connected to the negative terminal of its battery-heated filament, the electrode tends to collect positive ions which would otherwise contribute to the noise level of the tube as is especially true in the case of filamentary cathodes that are of coated 20 limited extent.

The invention will be better appreciated from the following detailed disclosure of an illustrative embodiment which is shown in the accompanying drawings:

Fig. 1 is a fragmentary longitudinal sectional view of an illustrative tube embodying the invention;

Fig. 2 is a transverse sectional view of the tube in Fig. 1 along the line 2—2; and

Fig. 3 is a fragmentary sectional view along the line 3—3 in Fig. 2.

Referring now to the drawings, a vacuum tube is shown having an upper portion 10 of its envelope wall formed of glass and the lower portion 12 of its wall formed of metal. The bottom of the envelope includes a metal ring 14 joined to wall portion 12, and glass plug 16 which 30 incorporates sealing tip 18 and provides mutually insulated seals for several of the leads emerging from electrodes.

Internally, filamentary cathode 20, consisting of two parts 20a and 20b, is stretched taut across an aperture 22 in mica wafer 24 that is carried by four supporting rods 40 26 secured to ring 14. The terminals of cathode 20 are connected to leads 28 and 30 which are sealed through glass plug 16. The terminals of the cathode 20 are connected to the leads 28, 30 through L-shaped conductive supports 28a, 30a. Coil spring 32 engages the midpoint 45 of the cathode to maintain its tension. Portions 20a and 20b of the cathode which extend across aperture 22 in the bottom mica are coated with electron-emissive material. In the portions of the filamentary cathode that are directly in contact with mica 24 there is a slight cooling, in comparison to the coated cathode portions above aperture 22. However the entire filamentary cathode passes heating current, and all its coated portions contribute to the electron stream.

In addition to filamentary cathode 20, included in the tubes described in the copending patent applications mentioned above, the further electrodes include positive grid 34 and dynode 36, which is a secondary-emissive electrode. The secondary-emission ratio of the dynode is purposely enhanced by application of such materials as magnesium oxide or caesium oxide or other comparable materials 55 known in the art. The term "secondary-emissive electrode" is not intended to include electrodes that may emit some small number of secondary electrons but, rather, electrodes having surface characteristics adapting them to emit secondary electrons copiously upon bombardment by incident electrons. Grid 34, of wire mesh in the illustration, is convex toward the cathode and is secured to the annular internal extension 38 of metal envelope portion 12. The extension 38 serves as a terminal for the application of appropriate biasing potentials 60 to the grid 34. The grid is of a refractory metal such as tungsten so as to withstand the heating usually char-

acteristic of positive-grid operation. Dynode 36 is sealed through the upper envelope portion 10 at a point not shown. In the tube thus far described, with appropriate positive potentials applied to grid 34 and dynode 36, the cathode current will reach a value limited by space charge in the region of the cathode, and will be approximately proportional to the length of the coated sections 20a and 20b of the filament, to the three-halves power of the voltage at the grid, and in approximate inverse proportion to the distance between the grid and the filament. In view of the direct relation between the coated length and current, and also in view of the fact that difficulty is experienced in maintaining accurate dimensioning of the coated length of filament, intolerably wide variations in space-charge-limited current are normally to be expected. Furthermore, while the active portion of the grid, the mesh in this specific tube, is closest to the cathode and therefore draws a large share of the cathode or primary electron emission, the grid support 38 can be expected to draw a share of the cathode current and thereby reduce the tube efficiency and increase the burden on the power supply. Especially in portable applications, the power supply is of limited capacity. In passing let it be understood that the term "grid" is used in the broad sense to mean any electron-permeable electrode, unless specifically indicated otherwise.

In order to improve the tube in the face of the foregoing conditions, an additional electrode 40 having an aperture 40a has been added, the electrode being in the form of a cupped disc larger in outer diameter but advantageously smaller in inner diameter than the aperture in grid support 38. The aperture 40a can be made larger than the active portion of the grid but then it should be operated at negative bias if it is to shield the grid support that is inactive. Electrode 40 is supported by and confined between a pair of centrally apertured micas 42 and 44 which are conveniently secured to rods 26, and has its own lead 46 sealed through glass plug 16. Electrode 40 thus has an externally-available terminal for application of any suitable potential or for connection as at 48, Fig. 3, to the cathode itself where desired. Alternatively, electrode 40 could be connected to the cathode internally of the tube; but it would then not be available for biasing when desired, or for measurement of the residual gas in the tube.

Electrode 40 constitutes a mask, or an electrostatic shield which intercepts electrostatic lines between the cathode and the inactive portions of the grid structure that are close enough to the cathode to draw appreciable current. Electrode 40 is conveniently positioned about midway between cathode 20 and positive grid 36, and has the effect of closely regulating the value of cathode current despite increases above specifications in the coated length of filamentary cathode. In the improved tube, the length of cathode coating, which is difficult to duplicate accurately, is much greater than in the tube previously disclosed so that it is not a controlling factor in the total cathode current; this function is now taken over by electrode 40, the aperture of which is more readily and accurately duplicated from tube to tube. Improved uniformity of cathode current is thus achieved. Due to the greater coated length, the cathode current is reduced for longer tube life and better uniformity among tubes.

What is claimed is:

1. An electron-discharge tube of the high-vacuum positive-grid type comprising a secondary-emissive anode, a substantially planar grid constructed to withstand the heating of positive-grid operation, and a filamentary cathode, all mounted in an envelope in the order named in substantially parallel planes, an annular metal support and terminal joined to said grid and extending radially therefrom, a metal electrode interposed between said filamentary cathode and said grid and having an aperture therein substantially smaller than said positive-grid, and

means for applying a biasing potential to said metal electrode.

2. An electron-discharge device comprising a planar grid, an annular metallic support and terminal centrally apertured and joined at the apertured edge to said grid, a filamentary cathode extending in a plane generally parallel to said grid, a disc-like electrode having an aperture therein and interposed between said filamentary cathode and said grid, said aperture being smaller than the extreme transverse limits of said filamentary cathode and said grid, and means including a terminal externally of said device for applying a biasing potential to said disc-like electrode.

3. A high-vacuum positive-grid electron-discharge tube comprising a tensioned filamentary cathode having a length coated with electron-emissive material, an insulating wafer supporting said filamentary cathode and locating said coated portion in a plane, a grid of refractory metal directly opposite said cathode, and a centrally apertured disc interposed between said cathode and said grid, the periphery of said disc being gripped between additional insulating wafers assembled against said cathode-supporting wafer, the lateral extent of the coated portions of said filamentary cathode being greater than the aperture in said disc.

4. An electron-discharge tube comprising a filamentary cathode having portions coated with electron-emissive material, a generally parallel grid of refractory wire supported opposite said cathode, and an electrode interposed between said cathode and said grid, said electrode having an aperture therein smaller in lateral dimension than the lateral extent of both said cathode and said grid, and means for applying a biasing potential to said electrode.

5. An electron-discharge tube comprising a filamentary cathode having portions coated with electron-emissive material, a refractory grid electrode supported opposite and generally parallel to said cathode, a further electrode on the side of said refractory electrode opposite the cathode side thereof, and a shielding electrode between said cathode and said grid electrode having an aperture therein smaller in lateral dimension than the extent of said coated portion of said filamentary cathode, and means including a terminal externally of said tube for applying a biasing potential to said shielding electrode.

6. An electron-discharge device comprising a cathode, a grid of refractory metal, and a secondary-emitting electrode mounted in an envelope in the order named, the improvement consisting of a further electrode between said cathode and said grid having a central aperture for primary electron passage shielding said cathode from secondary electrons that may penetrate said grid, and means connected to said further electrode and including a terminal externally of said envelope for applying a biasing potential to said further electrode.

7. An electron discharge tube including an evacuated envelope, a filamentary cathode having plural strands disposed in a plane and provided with supporting and tensioning means to maintain the strands in that plane, a grid, and a secondary emissive electrode, said grid and electrode having active portions in closely adjacent planes substantially parallel to that of the cathode, and a shield interposed between the cathode and the grid, said shield having a centered aperture of smaller extent than the transverse extent of said strands.

8. An electron discharge tube including an evacuated envelope, a cathode support, a filamentary cathode having portions coated with electron emissive material, said portions being disposed in a plane defined by said cathode support tensioning means maintaining said filament in said plane, an electrode having an active surface substantially parallel to the plane of the cathode, and a shielding electrode between the active portions of the cathode and said parallel electrode, said shielding electrode having an aperture smaller in lateral dimension than the extent of said coated cathode portion.

9. An electron-discharge tube including an evacuated

envelope, a filamentary cathode having plural strands disposed in a plane, support and tensioning means operatively connected to said filamentary cathode to maintain said strands in said plane, a grid, a secondary-emissive electrode, said grid and secondary-emissive electrode having active portions in closely adjacent planes substantially parallel to the plane of said filamentary cathode, a shielding electrode interposed between said cathode and said grid, said shielding electrode having a central aperture of smaller extent than the transverse extent of said strands of said filamentary cathode, and means for applying a bias potential to said shielding electrode.

10. An electron-discharge tube of the high-vacuum positive-grid type comprising a secondary-emissive anode, a substantially planar grid constructed to withstand the heating of positive-grid operation, and a filamentary cathode, all mounted in an envelope in the order named in substantially parallel planes, an annular metal support and terminal joined to said grid and extending radially therefrom, a metal electrode interposed between said

filamentary cathode and said grid and having an aperture therein, and means for applying a biasing potential to said metal electrode.

11. An electron-discharge device comprising a planar grid, a filamentary cathode extending in a plane generally parallel to said grid, a disc-like electrode having an aperture therein and interposed between said filamentary cathode and said grid, said aperture being smaller than the extreme transverse limits of said filamentary cathode, and means including a terminal externally of said device for applying a biasing potential to said disc-like electrode.
